UNITED STATES PATENT OFFICE.

HARRY W. BROADY, OF BAYSIDE, NEW YORK, ASSIGNOR TO AMERICAN BALSA COMPANY, INC., A CORPORATION OF NEW YORK.

ENGAGING AND DISENGAGING GEAR FOR SHIPS' BOATS.

1,319,675.

Specification of Letters Patent.

Patented Oct. 21, 1919.

Application filed February 11, 1918. Serial No. 216,642.

To all whom it may concern:

Be it known that I, HARRY W. BROADY, a citizen of the United States, and residing at Bayside, in the county of New York and 5 State of New York, have invented a new and Improved Engaging and Disengaging Gear for Ships' Boats, of which the following specification is a full disclosure.

This invention relates to improvements in 10 engaging and disengaging gear for ships' boats.

By the use of my invention, I am enabled 15 to produce an engaging and disengaging gear which may be released under a load or when the boat is being water-borne or towed; and which will be so arranged that all the parts 20 of the device readjust themselves automatically for engaging so soon as the strain or power is taken off the pull-chain and at the same time will lock the hook against movement when the gear reaches its engaging position so as to prevent releasing accidentally through any agency other than the pull-chain. Furthermore, the said gear is so arranged 25 that it will be impossible to lock or stick either in fully released position or in any other intermediate position.

Another feature of my invention enables 30 the ring of the falls, when the device is in engaging position to be freely moved inwardly into engagement with the hook but will, without special manipulation, prevent outward movement of such ring to disengage the same while the hook is in such engaging 35 position and said gear will furthermore automatically free the ring from such restraint when the device reaches its releasing position.

To these ends I provide in combination 40 with a pivoted and counterweighted tripping hook which is suitably supported, a power-multiplying device or system of levers, preferably pivotally mounted adjacent to the hook and connected thereto in such 45 manner that when the counter weight swings the hook into engaging position it will also cause the lever parts of the device to be automatically moved into position to form a toggle joint and thus through their connection 50 with the hook lock the same in such engaging position against movement by any other agency than through a suitable pull-chain secured to such lever. Preferably the hook and counter weight are formed in two

parts and the counter weight is pivoted to 55 the hook so that any movement thereof will cause the hook to be swung around its pivot from engaging to disengaging positions and vice versa. Furthermore, the lever parts are so arranged that one of them forms a 60 continuation or shank of the hook and when such levers are actuated the hook will be caused to have a closing and opening movement in relation to said shank part or lever so that the ring of the falls may be more 65 readily freed when the parts are in releasing position. As illustrated, the pivoted tripping-hook has pivoted to it, what I shall term, a shank-lever provided with a suitable counter weight which shank lever forms 70 a continuation or shank of the hook and this shank lever furthermore has integrally formed therewith a rearward extension which has a pivotal connection with a link which is, in turn, pivoted to the supporting 75 bracket adjacent to the hook pivot, the parts being arranged in such relationship that when the hook is in engaging position the pivotal connection first between the shank lever and hook and second, between the rear- 80 ward extension and the link, and, third, between link and supporting bracket, will be in alinement and produce a toggle locking-joint which will lock the hook against accidental movement in its engaging position 85 and furthermore, these parts of the gear are so arranged that the said rearward extension will abut against the link pivot or a suitable hub thereon to limit its movement to engaging position and will abut against 90 the hook pivot or a suitable hub thereon when it is moved to its extreme releasing position, in which position the parts are prevented from locking.

When it is desired to provide an automatic ring-retaining device in combination with the gear, I preferably provide a pawl which is weighted with the counter weight and pivoted to the shank lever and so arranged as to move pivotally on the said shank 100 lever a limited distance against the action of the said weight in one direction only so as to permit the ring to be moved through the mouth of the hook or through the space between the shank lever and the end of the 105 hook in one direction but to prevent or stop any movement in the opposite direction so that when the ring is once in place it will be

5 retained beneath the hook until the toggle-lever joint hereinabove described has been broken and the hook moved to releasing position, in which position the relative disposition of the hook and shank lever will be such as to completely free the mouth of the hook and to permit the exit of the ring therefrom.

10 Other objects will be in part obvious from the annexed drawing and in part indicated in connection therewith by the following analysis of this invention.

15 This invention accordingly also consists in the features of construction, combination of parts and in the unique relations of the members and in the relative proportioning and disposition thereof, all as more completely outlined herein and in said drawings.

20 To enable others skilled in the art so fully to comprehend the underlying features that they may embody the same by numerous modifications in structure and relationship of parts contemplated by this invention, drawings depicting a preferred form have been annexed as a part of this disclosure, and in such drawings like characters of reference denote corresponding parts throughout all the views, of which:—

25 Figure 1 is a plan view of a boat embodying an installation of my improved engaging and disengaging gear.

Fig. 2 is a large side elevation of one of the gears shown in Fig. 1;

30 Fig. 3 is a front elevation of the gear shown in Fig. 2;

Fig. 4 is a plan view of the gear shown in Figs. 1 to 3 inclusive;

Fig. 5 is a side elevation of a slightly modified installation of my said gear;

35 Fig. 6 is a plan view of an installation shown in Fig. 5;

Fig. 7 is a front elevation, partly in section, of the gear shown in Fig. 5;

40 Fig. 8 is another side elevation of a modified form of my invention embodying a ring retaining pawl;

Fig. 9 is a similar side elevation showing the gear in released position;

45 Fig. 10 is a section on the line 10—10 of Fig. 8; and

Fig. 11 is a section on the line 11—11 of Fig. 8.

50 Referring now to these drawings, 1 indicates a boat and 2 the keel thereof. To 55 the keel at opposite ends of the boat 1 are, as shown, mounted my improved disengaging gears, the gears at opposite ends being connected by pull-chains 3^a to a common releasing handle 4.

60 The engaging and disengaging gear which forms the subject matter of this invention, embodies, as shown, a hook 5 which is mounted on a fixed pivot 6 in a bracket 7 suitably secured by rivets or other fastening devices 65 8 to the keel 2 of the boat 1. To the rear

end of the hook 5 is pivoted at 9^a, what I shall term, a shank-lever 9 which, as shown in Figs. 1 to 7, is provided integrally with a counter weight 10 and has a rearwardly extending arm 11 which is pivoted at 12 to 70 a link 13 which, in turn, is pivoted at 14 to the bracket 7. The parts are so arranged

that when the gear is in the engaging position shown in full lines in Figs. 2 and 5, the pivots at 9^a, 12 and 14 will be in alinement 75 with each other and a toggle-joint will be produced whereby the hook will be locked against movement except through the agency

of the pull-chains 3 and the parts will automatically swing into position to form this 80 toggle-joint through the action of the counter weight 10. As illustrated, the rearward extension 11 of the shank lever 9 is bifurcated, and when the gear is in engaging and

locked position, the edge 11^a of such extension 85 will abut against the hub 13^a of the link 14 so as to limit the rearward movement of the parts. When the parts are, by

a pull upon the chain 3, swung into releasing position as illustrated in dotted lines 90 in Fig. 2, the said rearward extension, as

shown particularly in Figs. 2 and 8, will abut against the hub 5^a of the hook 5, as

shown at 11^b in Figs. 2 and 9, whereby the

forward movement of the parts is limited 95 and the device is prevented from locking in

its disengaging position. In Figs. 5, 6 and

7 I have illustrated an installation of my

gear supported by one of the thwarts 15 which is slotted as at 16 and provided with

100 a supporting bracket 17, the installation being reinforced by reinforcing strips 18 which are mounted on the pivot 6 at one

end and secured to a double bracket 19 at the opposite end which is, in turn, connected 105 to the keel 2 of the boat. These supporting strips have attached thereto, a rearward extension 20 in which the link 13 is pivoted.

The supporting strips 19 also support a pulley-block 21, the pulley-block 21 having 110 a pulley 21^a around which the chain 3 is adapted to be led. In other respects the installation is the same as that illustrated in

Figs. 1 to 4.

115 In Figs. 8 to 11 I have illustrated a form of gear which is in all respects similar to the gear shown in Figs. 1 to 4 inclusive except

that the shank lever 9 instead of being provided with an integral counter weight is bi-

furcated at 9^b and has pivoted thereto at 22, 120 a pawl 23 which has integrally formed

therewith the counter weight 10^a. The pawl 23 is so arranged in relation to the shank

lever 9 that it is free to move in one direction as illustrated in dotted lines in Fig. 8 125

against the action of the weight 10^a but is stopped from moving in the opposite direc-

tion by co-operating abutments 9^c and 23^a on the shank lever 9 and pawl 23, respectively. Obviously, a ring such as indicated in dotted 130

lines at 24 may be passed upwardly between the shank lever 9 and the end of the hook 5 by simply pressing the ring against the said pawl when the counter weight 10^a will be 5 swung on its pivot to permit the entrance of such ring. So soon, however, as the ring passes the pawl the weight will automatically assume the position shown in full lines in Fig. 8 and the ring will thereupon be 10 locked in position beneath the hook and above the pawl so that it will be impossible to release the same (without specially manipulating the weight) during the time the gear is in its engaging position. When, 15 however, the shank lever and weight are swung forwardly by the pull-chain 3 the hook will be swung around on its pivot in such relationship to the said shank lever 9 as to free the mouth of the hook and permit 20 the ring to move freely therefrom. So soon as the pull is relieved from chain 3, however, the weight 10 will cause the parts to resume the initial position shown in Fig. 8 and the pawl 23 will again assume its 25 mouth-blocking position.

The operation of the device will be obvious from the foregoing description.

I claim:

1. The combination with a pivoted, counter-weighted tripping hook and means for supporting the same, of power-increasing levers having a pivotal connection with the hook and a pivotal connection with a suitable support adjacent to the said hook, and means 30 for actuating one of such levers to swing the hook on its pivot from engaging to disengaging position.

2. The combination with a pivoted, counter-weighted tripping hook adapted to be swung 40 on its pivot from engaging to disengaging position and means for supporting the same, of a plurality of levers, one having a pivotal connection with the hook at one end and another having a pivotal connection with a 45 suitable support at the opposite end, the said levers being arranged to produce a toggle joint when the said hook is in engaging position, whereby the said hook will be locked in said engaging position against movement 50 except through actuation of one of said levers.

3. The combination with a tripping hook and means for pivotally supporting the same, of a shank lever having a pivotal connection with said hook; a counterweight associated with said shank lever, and means 55 for moving said shank-lever and its associated weight to swing said hook about its supporting pivot and also to move said hook and shank lever relatively on their pivotal connection.

4. The combination with a tripping hook, and means for pivotally supporting the same, of a shank lever having a pivotal connection with said hook; a counterweight as-

sociated with said shank-lever; a link having a pivotal connection with a suitable support at one end and with said shank lever at the opposite end, the said pivotal connection of the hook with the shank-lever, of the 70 shank-lever with the link and of the link with the support being in alinement to form a toggle joint when the hook is in engaging position, and means for moving said shank lever to swing the hook on its pivot. 75

5. The combination with a suitable hook, pivoted to a suitable fixed pivot, a shank lever having a pivotal connection with the said hook, a counterweight associated with said shank-lever; a link having a fixed pivotal connection with a suitable support at one end and with the shank lever at the opposite end, an abutment on said fixed pivotal connection of the link for limiting the movement of said shank-lever and hook 80 in one direction, and an abutment on the hook pivot for limiting the movement of the shank lever and hook in the opposite direction. 85

6. The combination with a suitable fixed 90 pivot, a hook pivoted to swing thereon, a bell-crank lever pivoted to the hook at its rear end and provided with a shank-lever arm and a rearward-extension arm, a weight 95 associated with said shank arm, another fixed pivot, a link lever pivotally connected to said last-mentioned fixed pivot at one end and having a pivotal connection at its opposite end with said extension arm, and means for applying power to one of said 100 levers to swing the hook about its fixed pivot and to simultaneously change the angle of the pivotal connection between the shank-lever and hook to open up the mouth of the latter. 105

7. The combination with a suitable hook and means for pivotally supporting the same, of a pawl pivotally associated with said hook at the mouth thereof; a weight associated with the said pawl below its 110 pivot,—the said pawl being adapted to be yieldingly moved against the action of the said weight in one direction only to permit the entrance into the said hook of a securing ring, but to prevent a withdrawal 115 thereof.

8. The combination with a suitable fixed pivot, a hook pivoted to swing thereon, a shank-lever having a pivotal connection with said hook; a link having a fixed pivotal 120 connection with a suitable support at one end and a movable pivotal connection with said shank lever at the opposite end; a pawl pivotally connected with said shank-lever in position to normally block the entrance to said hook and adapted to be moved in one direction only to permit entrance of a ring into said hook but to block a withdrawal thereof; a counterweight associated 125 with said pawl to retain the same normally 130

in entrance-blocking position and to move the hook from releasing to engaging position.

9. The combination with a suitable fixed pivot, a hook pivoted to swing thereon, a shank-lever having a pivotal connection with the said hook; and a pawl pivotally connected with said shank lever and retained in position thereon to normally block the entrance to said hook, said pawl being adapted to be moved in one direction only to permit entrance of a securing ring into the said hook, but to block a withdrawal thereof; a counterweight associated with said pawl and adapted to normally force the said pawl into entrance blocking position.

10. The combination with a suitable fixed pivot, a hook pivoted to swing thereon, a bell-crank lever pivoted to the hook at its rear end and provided with a shank-lever arm and a rearward-extension arm, a weight associated with said shank arm, and a link-lever pivotally connected at one of its ends to said rearward extension arm and having another pivotal connection with a fixed point located, when the hook is in engaging posi-

tion, between its said pivotal connection with the rearward extension arm and the pivoted hook, whereby a toggle joint is formed by the movement of the said pivotal connection of said rearward extension arm and link-lever to the side of said fixed pivot opposite to the pivoted hook.

11. The combination with a suitable fixed pivot, a hook pivoted to swing thereon, a shank-lever having a pivotal connection with said hook and adapted to be swung on said pivotal connection to opposite sides of a plane passing through the axes of said shank lever and the hook pivot, a weight associated with said shank-lever to swing the hook to engaging position, and means for applying power at said pivotal connection to swing the said hook and lever into disengaging position.

In witness whereof I hereunto subscribe my name, as attested by the two subscribing witnesses.

HARRY W. BROADY.
